UNITED STATES PATENT OFFICE.

HENRY PEARSON, OF SPRINGFIELD, MASSACHUSETTS.

RAILWAY-CAR.

1,078,373.

Specification of Letters Patent. Patented Nov. 11, 1913.

Application filed August 16, 1911. Serial No. 644,398.

To all whom it may concern:

Be it known that I, HENRY PEARSON, a citizen of the United States of America, and resident of Springfield, in the county of Hampden, and State of Massachusetts, have invented certain new and useful Improvements in Railway-Cars, of which the following is a full, clear, and exact description.

10 This invention relates to the construction of railway cars in which the side walls thereof are composed of sheet steel or iron. An object of this invention is to provide metallic car side forming sections which 15 have window openings therein, and which are combined with and connected to the posts forming the side of the framing of the car body, all made as units, to the end of the practicability of construction of such 20 units and of their being quickly, and in a stable manner, applied in combination one with another, and with the sill and upper longitudinal plate or beam of the car body, and whereby the side of the car will have 25 a very neat, tasteful and slight appearance, and will be devoid of overlapped joints or seams suggestive of "boiler plate construction."

Another object is to so construct the sectional units, comprising the sheet metal plates having window openings therein that suitably bent and integral portions of such plate sections constitute certain necessary window casing equipments. And under the 35 exercise of the invention extreme simplicity and economy of construction are attained.

The invention is described in conjunction with the accompanying drawings and set forth in the claims.

40 In the drawings:—Figure 1 is a side elevation of a portion of a railway car comprising my improvements. Fig. 2 is a vertical section on a larger scale on line 2—2, Fig. 1. Fig. 3 is a horizontal section on a 45 larger scale taken on line 3—3, Fig. 1. Fig. 4 is a horizontal section on line 4—4, Fig. 1. Fig. 5 is a perspective view of one of the sectional metallic units, a plurality of which form the side structure of the car body. 50 Figs. 6 and 7 are horizontal cross sectional views on an enlarged scale of features of construction hereinafter referred to.

I will first describe the car side forming units and thereafter indicate the manner of 55 their combination one with the other and

with the sill and upper beam, stringer or plate of the car body.

Each unit comprises a sheet metal plate section A of rectangular form of dimension vertically to extend from the sill to the 60 upper portion of the car and horizontally of but a fraction of the length of the latter.

Each sheet metal plate section has a window opening or openings B therein and their opposite vertical edge portions are 65 inwardly turned to form angular flanges a a so that those of the one plate section may be adjoined to those of adjacent plate sections and secured by rivets b or any equivalent fastenings. 70

The plate sections at the lower margin of each window opening are slightly outwardly turned, as shown at c and then inwardly return bent and approximately horizontally extended to form a strengthening rib 75 d constituting a window sill, the inner edge portion of each integral rib and window sill forming portion being vertically or upwardly extended to provide a reinforcing portion forming a horizontal window stop 80 f at the bottom of the window casing.

D D represent posts adjoining the inner side of the plate sections A adjacent the vertical margins of the window openings, and they have flanges g which are parallel with the vertical plane of the side of the car; and portions h of the plate sections at the vertical margins of the window openings are inwardly return bent around and engaged with the said flanges g g of the 90 posts to form in conjunction with such flanges of the posts vertical window stops while the vertical faces of the posts at the opposite boundaries of the window openings form the window casings or guides. 95

The upper edge portion of each metal plate section A is formed with a substantially horizontally turned flange i as shown in Figs. 2 and 5.

In the building of the car the floor frame 100 having been made, the units composed of the plate sections made as described and the posts D D connected therewith at lines adjacent the vertical margins of the window openings are brought to place and secured 105 by rivets j or otherwise on the outer face of the sill E.

The vertical flange edges of the plate sections are abutted and secured by the rivets b in conjunction with which connections an- 110

gle bars *k k*, as indicated in Fig. 6, may be advantageously used for strengthening the connection and stiffening the structure at the vertical seams. The plate beams or top 5 stringers *G* may be now brought to place receiving riveting connection therewith of the aforementioned flanges *i* of the plate sections *A* and with the tops of the posts *D D*, as shown in Fig. 2. As manifest, as 10 many of these units are to be employed as necessary and according to the length of the car; and at each end the car is made with a plate section *A²* understood as having the car end door opening *B²* therein 15 which extends from the bottom nearly but not entirely to the top end wall forming plate section. The said car end plate section has its vertical edge portions made with inturned flanges *m* for connection with the 20 curved thin metal corner posts *H H*, the edges of which are correspondingly flanged for abutment against the flanges *m* of the car end plate section and also inturned flanges *a* of the car side plate sections *A*. 25 The hook-like flanges *h* on the vertical side edges of car side plate sections *A*, which have wrapping engagement around the flanges of the posts *D*, may be secured to such flanges by any means desired, as, for 30 instance, by brazing or welding by processes known to be practicable for such operations, or they may be secured by mechanical fastenings.

In the example of the units for forming 35 the sides of the car body here illustrated, mullion windows are shown, in which case, as represented in Figs. 2 and 3, post-like bars *D²*, U-shaped in cross section and having outwardly turned flanges, similar to the 40 posts *D*, but of smaller cross sectional dimension, are employed, around the flanges of which the marginal portions of the sheet metal which, is comprised as an integral part *l* of the plate section *A* and which 45 forms the divided window openings, are wrapped.

The plate sections *A* instead of being adjoined at their vertical edges by the connection one with the other of the inwardly 50 turned flanges *a a* may be simply butt joined as shown in Fig. 7 and connected and retained in plane with each other by the internally applied vertical metal plates or thin bars *u* secured by rivets *v* as shown in 55 Fig. 7.

I claim:—

1. In a railway car body, in combination, metal plate sections adapted to form the

car side wall and having window openings therein, posts adjoining the inner sides of the plate sections adjacent the vertical margins of the window openings, said posts having flanges parallel with the plane of the side of the car, the vertical margins of the window openings being inwardly return bent around said flanges to form, in conjunction with said flanged posts window stops, and said plate sections having their portion at the lower borders of the window openings inwardly bent and marginally upturned to form strengthening ribs.

2. In a railway car body, in combination, metal plate sections to form the car side wall having window openings therein, having their opposite vertical edges adjoined and united, and posts adjoining the inner side of the plate sections adjacent the vertical margins of the window openings and having vertically extending flanges parallel with the plane of the side of the car,— 80 the portions of the plate sections at the vertical margins of the window openings being inwardly return bent around said flanges to form window stops while the transverse faces of the posts form window guides.

3. In a railway car body, in combination, the sill and upper longitudinal plate beam, metal plate sections to form the car side wall having window openings therein, having their opposed vertical edges adjoined and united, and posts adjoining the inner sides of the plate sections adjacent the vertical margins of the window openings and having flanges parallel with the plane of the 95 side of the car,—the portions of the plate sections at the vertical margins of the window openings being inwardly return bent around said flanges to form, in conjunction with such flanged posts, window stops, and 100 said plate sections having their portions at the lower borders of the window openings inwardly bent and marginally upturned to form strengthening ribs, and having their upper edges angularly turned to form 105 flanges, adjoined and fastened to the plate beam, while the lower portions adjoin the outer side of the car sill and are fastened thereto.

Signed by me at Springfield, Mass., in 110 presence of two subscribing witnesses.

HENRY PEARSON.
